ADJUSTABLE STAPLING MACHINE

Bernard Edward Shlesinger, Jr., Falls Church, Va.

Application May 21, 1953, Serial No. 356,540

11 Claims. (Cl. 1-3)

1

This invention relates to improvements in stapling machines, punches and the like of the type generally referred to as "desk" staplers or punches.

Present machines are limited in use by the depth of their throat. Business offices are constantly being faced with the problem of stapling papers at points remote from their edge and beyond the scope of the machines now available.

It is an object of this invention to provide a stapling machine or the like capable of stapling at points remote from the edge of the paper.

It is a further object of this invention to provide a stapling machine that is no larger than those presently in use, but which is capable of stapling at remote points.

A still further object of this invention is to provide a stapling machine for clerical use that is adjustable.

Another object of this invention is to provide an adjustable stapling machine that is compact.

Yet another object of this invention is to provide an adjustable stapling machine, without sacrificing staple capacity.

A further object of this invention is to provide a stapling machine which is readily adjustable to a series of positions.

A still further object of this invention is to provide an adjustable stapling machine that is rugged and economical to manufacture.

Another object of this invention is to provide a stapling machine having an adjusting mechanism that will not interfere in any manner with the operation of the machine.

These and other objects and advantages of this invention will be apparent from the following description and claims.

In the accompanying drawings which illustrate by way of example various embodiments of this invention:

Fig. 1 is a side elevation of a stapler embodying this invention and showing the stapler in closed position;

Fig. 2 is a side elevation of the stapler in extended position;

Fig. 3 is a section on the line 3-3 of Fig. 1 looking in the direction of the arrows;

Fig. 4 is a section on the line 4-4 of Fig. 2 looking in the direction of the arrows;

Fig. 5 is a bottom plan view of a modified form of stapler;

Figs. 6 and 7 are sections on the line 6-6 of Fig. 5 showing the detent in locking and in disengaged positions, respectively;

Fig. 8 is a side elevation of another modification of the stapler;

2

Fig. 9 is a section taken on the line 9-9 of Fig. 8 looking in the direction of the arrows.

In Figures 1 to 4, the stapling machine comprises an anvil support having a front section 10 and a rear section 11. Resilient pads 12 act as cushions or castors for the machine and are secured to the front and rear sections of the anvil support by cement or other suitable means. An anvil 13 is carried on front section 10. A pair of brackets 14 are carried by the rear section 11 and act as support for pivot pin 15. A stapling head support comprising a front section 20 and a rear section 21 is supported on pivot pin 15 by means of ears 22 carried by the rear section 21. Mounted on front section 20 is a conventional staple driving head 23 provided with a plunger of staple driver 24 to which is secured a suitable striking button 25. A conventional staple feed mechanism part of which is shown at 26 is supported and housed in front section 20. Riveted to rear sections 11 and 21 by means of rivets 30 are straps 31 and 32 which serve as carriages for the front sections 10 and 20. Fingers 33 and 34 (Figs. 3 and 4) which can be punched out of the anvil and stapling head supports serve as guides for stops 31 and 32. It is understood that other types of guides may be provided such as slotted tracks and the like. Straps 31 and 32 have at their forward ends, stops 35, which are of a width sufficiently narrow to pass between fingers 33 but wide enough to engage fingers 34 when the front sections are extended (Figures 2 and 4). The fingers 33 located on the rear sections 11 and 21 forward of the rivets 30, prevent pivotal movement of the straps about the rivets 30. Similarly the rear fingers 33 on the front sections prevent pivoting and provide rigid support for the front sections when extended.

40 *Operation.*—By merely grasping the rear sections 11 and 21 in one hand and the front sections 10 and 20 in the other and pulling in opposite directions, the sections are separated from one another. When fully extended, the stapling head and anvil are automatically aligned. For in between adjustment indicia on the upper surfaces of the straps 31 and 32 may be used.

Figures 5, 6 and 7 show a modification having adjusting rods 40 and 41. Rings 42 and 43 serve 50 as guides for rods 40 and 41. Such rings can be cast integrally with the anvil support or spot welded thereto.

Guide ring 43 is substantially longer than rings 42 to prevent pivoting and provides a rigid connection for the anvil support when extended. To prevent the adjusting rods 40 and 41 from slip-

ping through the guide rings 42 on rear section 11, lugs 45 are formed on rods 40 and 41. A similar lug 46 is formed on the front of rod 41 for the same purpose. Rod 41 is notched as at 47 to permit selective adjustment between the parts.

A locking mechanism (Figures 6 and 7) for rod 41 is provided in front section 10. A plunger 48 having a detent portion 49 is supported by one side wall of front section 10 and an inner bracket 50. A spring 51 interposed between inner bracket 50 and a collar or flange 52 on plunger 48 tends to keep the open ended plunger in a locking position.

Operation.—By depressing the plunger 48 (Figure 7), rod 41 is permitted to slide in guide rings 42. Upon release of the plunger 48, detent portion 49 (Figures 6 and 7) of the plunger 48 drops into one of the notches 47 (Figure 6).

It will be obvious to those skilled in the art that the rods of the above modification can also be used as the stapling head support adjusting mechanism.

Figures 8 and 9 show another modification in which both the stapling head support and anvil support are simultaneously adjusted. In this modification two pairs of racks 70 and 71 are secured to the front sections 10 and 20 by means of rivets 72 or other suitable means such as welding. Two pairs of meshing pinions 73 and 74 engage racks 70 and 71 respectively. Pinions 73 are fixed to shaft 75 (Figure 9) which is carried on the rear section 11a through which racks 70 slide. Pinions 74 are fixed to pivot pin 15a which connects rear sections 11a and 21a in a manner similar to pivot pin 15 heretofore described. Pivot pin 15a is extended to receive a turning knob 76 which is fixed to the pivot pin 15a by suitable means such as a set screw 77 (Figure 9). A similar knob could be provided on the opposite end of pivot pin 15a if desired. Guides 78 are secured to rear sections 11a and 21a to prevent lateral movement of racks 70 and 71 and stops 79 prevent racks 70 and 71 from disengaging pinions 73 and 74. Indicia may be provided on any or all of racks 70 and 71 for measured adjustment.

Operation.—By rotating knob 76, meshing pinions 73 and 74 rotating in opposite directions as indicated by the arrows in Figure 8, act on racks 70 and 71 to extend or retract front sections 10 and 20.

While the invention has been described in connection with different embodiments thereof, it will be understood that it is capable of further modification, and this application is intended to cover any variations, uses, or adaptations of the invention following, in general, the principles of the invention and including such departures from the present disclosure as come within known or customary practice in the art to which the invention pertains, and as may be applied to the essential features hereinbefore set forth and as fall within the scope of the invention or the limits of the appended claims.

Having thus described my invention, what I claim is:

1. An adjustable stapling machine comprising an anvil arm, an anvil on said anvil arm, a stapling head carrying a driver and a magazine, arms connected to and extending rearwardly from said anvil arm and said stapling head respectively, means for pivotally mounting said last mentioned arms together, and means permitting relative adjustment of the distance between the

5 pivot means and the anvil and between the pivot means and the driver.

2. An adjustable stapling machine comprising a base having a front end section, a mid-section, and a rear end section, an anvil on said base front end section, a stapling head having a front end section, a mid-section, and a rear end section, a driver on said stapling head front end section, pivot means connecting said rear end sections together for pivotal movement of said stapling head relative to said base, and means permitting relative adjustment of one of said base end sections with said base mid-section and one of said stapling head end sections with said stapling head mid-section, said base mid-section and said stapling head mid-section being rigidly connected to the other base end section and the other stapling head end section respectively.

3. An adjustable stapling machine comprising a base having a front end section, a mid-section, and a rear end section, an anvil on said base front end section, a stapling head having a front end section, a mid-section, and a rear end section, a driver on said stapling head front end section, pivot means connecting said rear end sections together for pivotal movement of said stapling head relative to said base, and means adjustably connecting said base end sections with said base mid-sections and said stapling head mid-sections so as to allow for extension and contraction of said base and said stapling head.

4. An adjustable stapling machine comprising a base having a front end section, a mid-section, and a rear end section, an anvil on said base front end section, said base mid-section being rigidly connected to one of said base end sections, means on the other of said base end sections forming a guide for the base mid-section to be guided thereby so as to allow for extension and contraction of said base, a stapling head having a front end section, a mid-section, and a rear end section, a driver on said stapling head front end section, said stapling head mid-section being rigidly connected to one of said stapling head end sections, means on the other of said stapling head end sections forming a guide for the stapling head mid-section to be guided thereby so as to allow for extension and contraction of said stapling head relative to said base, and pivot means connecting said rear end sections together for pivotal movement of said stapling head relative to said base.

5. An adjustable stapling machine comprising a base having a front end section, a mid-section, and a rear end section, an anvil on said base front end section, said base mid-section being rigidly connected to said base rear end section, means on said base front end section forming a guide for said base mid-section to be guided thereby so as to allow for extension and contraction of said base, a stapling head having a front end section, a mid-section and a rear end section, a driver on said stapling head front end section, said stapling head mid-section being rigidly connected to said stapling head rear end section, means on the stapling head front end section forming a guide for the stapling head mid-section to be guided thereby so as to allow for extension and contraction of said stapling head relative to said base, and pivot means connecting said rear end sections together for pivotal movement of said stapling head relative to said base.

6. An adjustable stapling machine comprising

a base having a front end section, a mid-section, and a rear end section, an anvil on said base front end section, said base mid-section being rigidly connected to said base rear end section, means on said base front end section forming a guide for the base mid-section to be guided thereby so as to allow for extension and contraction of said base, a stapling head having a front end section, a mid-section, and a rear end section, a driver on said stapling head front end section, said stapling head mid-section being rigidly connected to said stapling head rear end section, means on said stapling head front end section forming a guide for the stapling head mid-section to be guided thereby so as to allow for extension and contraction of said stapling head relative to said base, said mid-sections being shaped in the form of straps, and pivot means connecting said rear end sections together for pivotal movement of said stapling head relative to said base.

7. An adjustable stapling machine comprising a base having a front end section, a mid-section, and rear end section, an anvil on said base front end section, said base mid-section being rigidly connected to said base rear end section, means on said base front end section forming a guide for the base mid-section to be guided thereby so as to allow for extension and contraction of said base, a stapling head having a front end section, a mid-section, and a rear end section, a driver on said stapling head front end section, said stapling head mid-section being rigidly connected to said stapling head rear end section, means on said stapling head front end section forming a guide for the stapling head mid-section to be guided thereby so as to allow for extension and contraction of said stapling head relative to said base, said mid-sections being shaped in the form of straps, pivot means connecting said rear end sections together for pivotal movement of said stapling head relative to said base, and stops on said mid-sections for engagement with said guide means to prevent disconnection of said base front end section from said base mid-section and said stapling head end front section from said stapling head mid-section.

8. An adjustable stapling machine comprising a base having a front end section, a mid-section, and a rear end section, an anvil on said base front end section, said base mid-section being rigidly connected to said base front end section, means on said base rear end section forming a guide for said base mid-section to be guided thereby so as to allow for extension and contraction of said base, a stapling head having a front end section, a mid-section, and a rear end section, a driver on said stapling head front end section, said stapling head mid-section being rigidly connected to said base mid-section.

idly connected to said stapling head front end section, means on the stapling head rear end section forming a guide for the stapling head mid-section to be guided thereby so as to allow for extension and contraction of said stapling head relative to said base, and pivot means connecting said rear end sections together for pivotal movement of said stapling head relative to said base.

10 9. An adjustable stapling machine comprising an anvil arm, an anvil on said anvil arm, a stapling head carrying a driver and a magazine, racks connected to and extending rearwardly from said anvil arm and said stapling head respectively, means for pivotally mounting said racks together, and pinions mounted on said pivot means cooperating with said racks permitting relative adjustment of the distance between the pivot means and the anvil and between the pivot 15 means and the driver.

20

10. An adjustable stoppling mechanism

10. An adjustable stapling machine comprising an anvil arm, an anvil on said anvil arm, a stapling head carrying a driver and a magazine, two pairs of parallel racks, one pair connected to and extending rearwardly from said anvil arm, and the other pair connected to and extending rearwardly from said stapling head, means for pivotally mounting said two pairs of parallel racks together, and two pairs of parallel pinions mounted on said pivot means, one pair cooperating with said anvil arm racks, the other pair cooperating with said stapling head racks, permitting relative adjustment of the distance between the pivot means and the anvil and between the pivot means and the driver.

11. An adjustable stapling machine comprising an anvil arm, an anvil on said anvil arm, a stapling head carrying a driver and a magazine, two pairs of parallel racks, one pair connected to and extending rearwardly from said anvil arm, and the other pair connected to and extending rearwardly from said stapling head, means for pivotally mounting said two pairs of parallel racks together, two pairs of parallel pinions mounted on said pivot means, one pair cooperating with said anvil arm racks, the other pair cooperating with said stapling head racks, permitting relative adjustment of the distance between the pivot means and the anvil and between the pivot means and the driver, and a turning knob connected to one set of parallel pinions.
